(57) **CLAIM**

The ornamental design for a case for electronic device, as shown and described.

DESCRIPTION

FIG. 1 is a perspective view including the front, bottom, and side of an embodiment of a case for electronic device;

FIG. 2 is a front elevation view of the case for electronic device of FIG. 1;

FIG. 3 is a rear elevation view of the case for electronic device of FIG. 1;

FIG. 4 is a side elevation of the case for electronic device of FIG. 1;

FIG. 5 is an opposite side elevation view of the case for electronic device of FIG. 1;

FIG. 6 is a top plan view of the case for electronic device of FIG. 1;

FIG. 7 is a bottom plan view of the case for electronic device of FIG. 1;

FIG. 8 is a perspective view including the front, top and opposite side of the case for electronic device of FIG. 1;

FIG. 9 is a perspective view including the front, bottom, and side of an embodiment of a case for electronic device;

FIG. 10 is a front elevation view of the case for electronic device of FIG. 9;

FIG. 11 is a rear elevation view of the case for electronic device of FIG. 9;

FIG. 12 is a side elevation of the case for electronic device of FIG. 9;

FIG. 13 is an opposite side elevation view of the case for electronic device of FIG. 9;

FIG. 14 is a top plan view of the case for electronic device of FIG. 9;

FIG. 15 is a bottom plan view of the case for electronic device of FIG. 9; and,

FIG. 16 is a perspective view including the front, top and opposite side of the case for electronic device of FIG. 9.
